Primary Examiner — Andrew T Nemeth

CLAIM

The ornamental design for a hanging automatic pet food dispenser, as shown and described.

DESCRIPTION

FIG. 1 is a front, left and top perspective view of a hanging automatic pet food dispenser, showing my new design; FIG. 2 is a rear view thereof; FIG. 3 is a top view thereof; FIG. 4 is a right side thereof; FIG. 5 is a left side view thereof; FIG. 6 is a top plan view thereof; FIG. 7 is a bottom view thereof; FIG. 8 is a bottom plan view thereof; and, FIG. 9 is an enlarged view of portion of FIG. 1 thereof. The broken lines shown in the drawings illustrate portions of the hanging automatic pet food dispenser that form no part of the claimed design.
